PRODUCTION OF ARTIFICIAL THREADS

Giovanni Campolunghi, Rome, Italy

Application October 25, 1937, Serial No. 170,950
In Italy November 11, 1936

1 Claim. (Cl. 57—2)

Several methods are already known for continuously transforming endless artificial filaments to staple fibre or in twisted threads of short fibres, but hitherto these methods have been never united directly with the spinning operation.

According to the known methods the said purpose was met either by cutting or by tearing the finished endless filaments to pieces of the desired length, and proceedings of this kind are described for instance in the United States Patent No. 2,012,723, or in the British Patent No. 424,683, or in the Austrian Patent No. 143,153 and in other patents.

On the contrary, the process according to the invention consists in the producing during the viscose spinning process according to the centrifugal system, of a thread which is not endless, but is formed by torn filaments. According to the invention the endless bundle comprising a plurality of single filaments, on its passage from the funnel to the spinning can, is conducted over a scabrous edge or an edge having cutting prominences, while, under the traction effect of the revolving can, it is obliged to slide on this scabrous edge provided on the lower end of the said funnel. In this way some of the single filaments forming the bundle are continuously torn or broken, and as the bundle of filaments is always turning round the scabrous edge of the channel 25 and always descending in the spinning can, after a certain time all of the single filaments will be torn in some point with the effect that the twisted thread collected in the spinning can will show the appearance and the qualities of a short fibre 30 thread.

The cutting surfaces used for tearing the single filaments may have a different degree of efficiency according to the number and the thickness of the single filaments which form the thread

and according to the count of the thread to be produced and to the desired length of its single filaments.

A device suitable for the realisation of the described proceeding is shown by way of example in the accompanying schematical drawing, but it has to be understood that this device may be modified in any details.

As it is shown in the drawing, the bundle F of single endless filaments enters from above in 10 the pipe A of the funnel and is then conducted by the inclined surface of the part B of this funnel in the narrow aperture of the part B having a scabrous edge or surface C, on which, by the friction effect of the bundle sliding around, several of the single filaments are always torn with the result that a thread formed by short fibres leaves the guide D being then twisted and collected in the revolving can.

The members A, B, C, D may be parts separated 20 the one from the other or united in a single piece according to the material chosen for them.

What I claim is:

Apparatus for the production of short-fibered twisted artificial threads comprising a funnel 25 through which a bundle of filaments may be passed for delivery to a revolving spinning can, said funnel being provided adjacent its lower end with a scabrous surface adapted to tear single filaments during their passage to the spinning can, 30 said funnel being further provided at said lower end and at a point beyond said scabrous surface with a smooth surface, said smooth surface being angularly arranged with reference to the axis of the funnel so that the threads may pass thereover during their passage at an angle from the funnel to the revolving can.

GIOVANNI CAMPOLUNGHI.
